UNITED STATES PATENT OFFICE.

FRANK A. BIEHN, OF CHICAGO, ILLINOIS.

CARBURETER.

No. 889,707.

Specification of Letters Patent.

Patented Dec. 25, 1906.

Application filed July 11, 1904. Serial No. 216,145.

To all whom it may concern:

Be it known that I, FRANK A. BIEHN, a citizen of the United States of America, and a resident of Chicago, in the county of Cook and State of Illinois, have invented certain new and useful Improvements in Carbureters, of which the following is a specification.

My invention relates to carbureters and devices for controlling the admission of fluid fuel to oil and gas engines.

The main objects of my invention are to provide improved means for vaporizing oil and fuel and mixing the same with air in its passage to the cylinder of an explosive-engine, to provide improved means for maintaining the proportions of air and fuel in proper relation to each other under the varying conditions arising during various changes of load, to provide in a device of this class an arrangement of valves for supplying fuel and air operated through the suction of the engine-cylinder readily adjustable relatively to each other and readily controlled to suit the various requirements of the engine, and to provide an improved form of governor operated by the suction of the engine-cylinder and adapted to automatically control the fuel-supply to maintain a fixed speed of the engine for each setting of the fuel-supply valves.

I accomplish these objects by the device shown in the accompanying drawings, in which—

Figure 1 is a vertical longitudinal section of a carbureter for oil-engines constructed according to my invention. Fig. 2 is a top plan of the same.

The framework of the carbureter shown consists of a hollow valve-casing comprising for convenience of construction a plurality of separable sections. The interior cavity 2 forms a mixing-chamber and is provided with an air-inlet 3, a fuel-inlet 4, and an outlet 5 for delivering the mixed fuel and air to an engine-cylinder, to which the carbureter is connected by means of a nipple threaded into the flange 6. The engine is not shown in the drawings. The fuel-inlet, air inlet and outlet are each controlled by a valve. The outlet-valve 7 is a pop-valve opening upwardly on the side of the outlet-passage 5 which is toward the engine-cylinder, so that

the said outlet-valve will be opened by the suction of the engine-cylinder when fuel is being drawn into the same through the movement of its piston. The outlet-valve 7 is loosely and slidably mounted on a rod 8, which extends upwardly, passing loosely through the top of the valve-casing and being threaded at 9 near its upper end to receive an adjusting-nut 10 and lock-nut 11. A piston is rigidly secured to the rod 8 and is vertically shiftable in the cylindrical bore 13 in the valve-casing above the outlet-passage 5 and is adapted to be moved toward the valve 7 through suction produced in the passage 14 by the intaking stroke of the piston in the engine-cylinder.

A helical spring 15 surrounds the rod 8 and bears between the piston 12 and the valve 7, normally urging the valve 7 into its closed position, but being adapted to yield to permit the opening of the valve 7 under the suction from the engine-cylinder. The tension of the spring 15 is controlled by the movement of the piston 12, which governs the action of the valve 7, as will be hereinafter described. A second helical spring 16 bears between the upper surface of the piston 12 and the top part 17 of the valve-casing, normally urging the piston 12 downwardly toward the valve 7. The upper surface of the piston 12 is exposed to the atmospheric pressure in the upper part of the bore 13, which communicates with the outer air through the aperture 18, while the lower surface of the valve 7 is exposed to the pressure of the gases in the mixing-chamber 2, which is normally a little below atmospheric pressure. The exposed area of the piston 12 is greater than that of the valve 7, so that the suction of the engine will urge the valve 7 toward its closed position. A third helical spring 19 bears between the nut 10 and the member 20, which is seated on the top 17 of the valve-casing and tends to urge the rod 8 upwardly, raising the piston 12 against the action of the spring 16 and yieldingly resisting downward movement of said piston. The member 20 is provided with a pair of cam-surfaces 21, which ride on shoulders 22 at diametrically opposite points on the valve-casing, and is thereby raised or lowered when the member 20 is turned by means of the lever 23, thus correspondingly raising or lowering the piston 12 and varying the tension of the spring 15 on

the valve 7. The lever 23 is connected by suitable links and mechanism (not shown) with the controlling-lever of the engine.

The air-inlet 3 is controlled by means of a valve 24, which is normally held in its closed position by the springs controlling the valve 7, the two valves being separated by the sleeve 25. The valve 24 is held in contact with the sleeve 25 by the spring 26, which bears on the nut 27 on the rod 8.

The fuel-inlet 4 is controlled by a needle-valve 31, which is threaded into a member 32 and locked in any position relatively of said member by means of a set-screw 33. The member 32 is provided with a transversely-extending arm 34, having therein a series of apertures 35 for receiving a swivel-stud 38 on the member 20. The apertures 35 in the arm 34 are preferably arranged in the arc of a circle having its center in the stud 38 when the lever 23 is in the position corresponding to the slowest speed of the engine. Each of the apertures 35 corresponds to a different throw of the needle-valve 31 for a certain movement of the lever 23, thus permitting of accurate adjustment of the throw of the needle-valve 31 to conform with various conditions of the atmosphere and qualities of the fuel. Besides admitting air to the mixing-chamber 30 through the inlet 3, a second air-inlet 39 is suitably located to deliver a fine jet of air across the top of the fuel-inlet 4 for atomizing the fuel as it is delivered to the mixing-chamber, and thereby insuring more thorough mixture when the fuel comes into contact with the air rushing into the mixing-chamber at the inlet 3.

An oil-reservoir 40 communicates with the fuel-inlet 4 through the tube 41. The reservoir 40 is connected with an oil-tank (not shown) and has an oil-inlet 46, controlled by a valve 47, operated by a float 48 for maintaining a constant depth of oil in the reservoir 40. The space in the reservoir 40 above the level of the oil communicates with the atmosphere in a roundabout way through the apertures 49 and 50. This tortuous disposition of the air-passage serves the purpose of preventing the oil from spilling out of the reservoir 40. The float 48 is preferably mounted centrally of the oil-inlet tube 41, so that the device may be tilted to a considerable angle without materially changing the level of the oil in the tube 41. This insures a uniform oil-supply for each setting of the valve and frees the same from disturbance by outside influences. The float 48 is mounted on a sleeve 43, loosely fitting on the tube 41 and connecting by a lever 44 with the valve 47. Communication between the inlet 4 and the oil-receptacle 40 is had through apertures 45. A push-rod 42 is provided for releasing the float 48 in case the same gets stuck at the upper end of the tube 41. The mechanism 65 of the oil-receptacle is already commonly un-

derstood in the art, and it is believed that it will not be necessary to describe the same in detail herein.

The operation of the device shown is as follows: Oil passes from the supply-tank to the oil-reservoir through the inlet-passage 46 and is maintained at a certain predetermined constant level in the reservoir by the float-controlled valve. During that part of the stroke of the engine-piston during which fuel is taken into the cylinder the suction of the engine-cylinder lifts the valves 7 and 24 and also causes a jet of oil to spurt through the inlet-passage 4. The jet of air entering the aperture 39 under the suction of the engine-cylinder atomizes the jet of oil issuing from the fuel-inlet 4, and the atomized fuel then mixes with the air which enters the inlet-chamber 2 through the air-inlet 3. The gas so mixed passes through the outlet-aperture 5 and is delivered through the passage 14 to the engine-cylinder. The tension on the spring 19 is adjusted by means of the adjusting-nut 10, so that when the lever 23 is in the position shown in Fig. 1 the valve 7 will open sufficiently under the suction of the engine-cylinder to admit the proper amount of gaseous fuel for the slowest speed at which the engine is to be run. The needle-valve 31 is also adjusted to regulate the admission of oil for such minimum speed by turning said needle-valve relatively of the member 32 when said member is in the position shown in Fig. 2: If when the engine is running at a certain speed the load should suddenly decrease, tending to speed up the engine, the increased suction, having a greater effect on the piston 12 than on the valve 7, would tend to decrease the opening of the valve 7, cutting down the amount of fuel taken into the cylinder and reducing the speed of the engine until the normal speed is reached for which the mechanism controlling said piston and valve has been set. It will be seen that the piston 12 thus acts as a governor and prevents the engine from exceeding the speed for which the governing mechanism is set. To increase the power of the engine, the lever 23 is turned in the direction of the arrow on Fig. 2. This causes the member 20 to move upwardly against the spring 19, lifting the piston 12, permitting the valve 7 to have a greater range of movement, and consequently admit the required greater amount of fuel. As the member 20 rotates the link 37 causes a corresponding rotation of the member 32. The member 32 has a left-hand thread 51 engaging the valve-casing, and consequently lifts the needle-valve 31 when the lever 23 is rotated in the direction indicated, thus increasing the oil-supply as the consumption increases. The cam-surfaces 21 on the member 20 are of such form that the setting of the governing mechanism from minimum to maximum speed is accomplished 130

by shifting the lever 23 through an angle of about ninety degrees. The corresponding angle of movement of the member 32 and the throw of the needle-valve 31 will depend upon the point at which the link 37 connects with the arm 34. To adjust the fuel-valve 31 for minimum speed, the lever 23 is turned to the position shown in Fig. 2 and the needle 31 is rotated within the member 32 until best results are obtained, the best position being determined by a noiseless exhaust, indicating complete consumption of the power supplied. To adjust the fuel-valve 31 for maximum speed of the engine, the lever 23 is thrown to its "wide-open" position and the stud 36 is shifted along the arm 34 until the best results are obtained. Movement of the lever 23 to any of its intermediate positions will of course cause a proportionate change in the setting of the valve 31, so that the fuel and air will always bear the proper relation to each other and to the requirements of the engine.

It will be seen that the arrangement of valves and the governing mechanism controlling the delivery of fuel to the engine corresponds exactly with the consumption of power at all times and is controlled by the movement of a single lever 23, thus making it possible to use the full expansive power of the fuel under all conditions of load and avoiding the necessity of shifting the spark to change the speed, as is generally done with the forms of carbureters in common use and which gives rise to great waste of fuel and loud exhaust.

It will be seen that numerous details of the construction shown may be altered without departing from the spirit of my invention.

40 What I claim as my invention, and desire to secure by Letters Patent, is—

1. In a device of the class described, the combination of a mixing-chamber having fuel and air inlets and having an outlet for delivering the mixed fuel and air to an engine-cylinder; a valve controlling said outlet, being normally urged toward its closed position and adapted to open through the suction of the engine-cylinder; a governing device for controlling the opening of said valve, being adapted to automatically increase the resistance to the opening of the valve through an increase in the suction of the engine-cylinder.

55 2. In a device of the class described, the combination of a mixing-chamber having fuel and air inlets and having an outlet for delivering the mixed fuel and air to an engine-cylinder; a valve controlling said outlet being normally urged toward its closed position and adapted to open through the suction of the engine-cylinder; a governing device for controlling the opening of said valve, being adapted to automatically increase the resistance to the opening of the valve

through an increase in the suction of the engine-cylinder; and means for varying the action of said governing device to change the speed of the engine.

3. In a device of the class described, the combination of a casing; a mixing-chamber having fuel and air inlets and having an outlet for delivering the mixed fuel and air to an engine-cylinder; a valve controlling said outlet, being normally urged toward its closed position and adapted to open through the suction of the engine-cylinder; a piston movably mounted in said casing and adapted to urge said valve toward a closed position when moved through the suction of the engine-cylinder, substantially as described.

4. In a device of the class described, the combination of a casing; a mixing-chamber having fuel and air inlets and having an outlet for delivering the mixed fuel and air to an engine-cylinder; a valve controlling said outlet, being normally urged toward its closed position and adapted to open through suction of the engine-cylinder; a piston adapted to be moved by the suction of the engine-cylinder and urge said valve toward a closed position; and regulating mechanism for controlling the movement of said piston, substantially as described.

5. In a device of the class described, the combination of a casing; a mixing-chamber having fuel and air inlets and having an outlet for delivering the mixed fuel and air to an engine-cylinder; a valve controlling said outlet, being normally urged toward its closed position and adapted to open through suction of the engine-cylinder; a piston adapted to be moved by the suction of the engine-cylinder and urge said valve toward a closed position; and a spring resisting the movement of said piston, substantially as described.

6. In a device of the class described, the combination of a casing; a mixing-chamber having fuel and air inlets and having an outlet for delivering the mixed fuel and air to an engine-cylinder; a valve controlling said outlet, being normally urged toward its closed position and adapted to open through suction of the engine-cylinder; a piston adapted to be moved by the suction of the engine-cylinder and urge said valve toward a closed position; a spring resisting the movement of said piston; and lever-controlled mechanism for varying the resistance of said spring, substantially as described.

7. In a device of the class described, the combination of a casing; a mixing-chamber having fuel and air inlets and having an outlet for delivering the mixed fuel and air to an engine-cylinder; a valve controlling said outlet and adapted to open through the suction of the engine-cylinder; a rod for guiding said valve; a piston mounted in said casing concentrically of said rod and adapted to be moved toward said valve by the suction of

the engine-cylinder; a spring bearing between said valve and piston; and means for controlling the movement of said piston, substantially as described.

5 8. In a device of the class described, the combination of a casing; a mixing-chamber having fuel and air inlets and having an outlet for delivering the mixed fuel and air to an engine-cylinder; a valve controlling said outlet and adapted to open through the suction of the engine-cylinder; a rod for guiding said valve; a piston mounted in said casing concentrically of said rod and adapted to be moved toward said valve by the suction of 70
10 the engine-cylinder; a spring bearing between said valve and piston; said piston being of greater diameter than said valve and adapted to overcome the suction on said valve and urge the valve toward a closed position; and means for controlling the movement of said piston, substantially as described.

9. In a device of the class described, the combination of a casing; a mixing-chamber 25 having fuel and air inlets and having an outlet for delivering the mixed air and fuel to an engine-cylinder; a valve controlling said outlet and adapted to open through the suction of the engine-cylinder; a rod for guiding 30 said valve; a piston mounted in said casing concentrically of said rod and adapted to be moved toward said valve by the suction of the engine-cylinder; a spring bearing between said valve and piston; said piston being of greater diameter than said valve and 35 adapted to overcome the suction of the valve and urge said valve toward a closed position; and means for yieldingly controlling the movement of said piston, substantially as described.

40 10. In a device of the class described, the combination of a valve-casing; a mixing-chamber having fuel and air inlets and having an outlet for delivering the mixed fuel and air to an engine-cylinder; a valve controlling said outlet and adapted to open through the suction of the engine-cylinder; a piston movably mounted in said casing and adapted to be moved toward said valve 45 through the suction of the engine-cylinder; a spring bearing between said valve and piston and adapted to normally urge said valve toward its closed position; a second spring normally urging said piston toward said valve; 50 and means for controlling the movement of said piston, substantially as described.

55 11. In a device of the class described, the combination of a valve-casing; a mixing-chamber having fuel and air inlets and having an outlet for delivering the mixed fuel and air to an engine-cylinder; a valve controlling said outlet and adapted to open through the suction of the engine-cylinder; a rod for guiding the movement of said valve; 60 a piston movably mounted in said casing con-

centrically of said rod and adapted to be urged toward the valve through the suction of the engine-cylinder; a spring bearing between said valve and piston; and suitable yielding governing mechanism for controlling the movement of said piston, substantially as described.

75 12. In a device of the class described, the combination of a casing; a mixing-chamber having fuel and air inlets and having an outlet for delivering the mixed fuel and air to an engine-cylinder; a valve controlling said outlet and adapted to open through the suction of the engine-cylinder; a rod loosely engaging said valve for guiding the movement thereof; a piston mounted on said rod and normally urged toward said valve through the suction of the engine-cylinder; a spring bearing between said valve and piston; a second spring bearing on said piston and 80 normally urging same toward said valve; a third spring adapted to yieldingly resist the action of said second spring and the suction of the engine-cylinder on said piston, substantially as described.

90 13. In a device of the class described, the combination of a casing; a mixing-chamber having fuel and air inlets and having an outlet for delivering the mixed fuel and air to an engine-cylinder; a valve controlling said outlet and adapted to open through the suction of the engine-cylinder; a rod loosely engaging said valve for guiding the movement thereof; a piston secured to said rod in alinement with said valve and being slidably mounted in said casing and normally urged toward said valve through the suction of the engine-cylinder; a spring bearing between said valve and piston; a second spring bearing on said piston and normally urging same toward said valve; 95 a third spring adapted to yieldingly resist the action of said second spring and the suction of the engine-cylinder on said piston; and mechanism for changing the tension on said third spring to control the action of said piston, substantially as described.

100 14. In a device of the class described, the combination of a casing; a mixing-chamber having fuel and air inlets and having an outlet for delivering the mixed fuel and air to an engine-cylinder; a valve controlling said outlet and adapted to open through the suction of the engine-cylinder; a rod loosely engaging said valve for guiding the movement thereof; a piston secured to said rod in alinement with said valve and being slidably mounted in said casing and normally urged toward said valve through the suction of the engine-cylinder; a spring bearing between said valve and piston; a second spring bearing on said piston and 115 normally urging same toward said valve; a third spring adapted to yieldingly resist the action of said second spring and the suction of the engine-cylinder on said piston; and a wedge member bearing between said third 120
125

spring and the casing and adapted to be moved on said casing to vary the tension on the third spring and thereby control the movement of said piston, substantially as described.

15. In a carbureter, the combination of a valve-casing; a mixing-chamber in said casing, having a fuel-inlet communicating therewith; a needle-valve controlling said fuel-inlet; a member supporting the needle-valve and having threaded connection with the casing and being adapted when rotated to move said needle-valve for varying the discharge of fuel through said inlet, said needle-valve being adjustable relatively of said member; an arm on the member for rotating the same; an operating-lever, and a link connecting said arm and lever, said link being adjustable at one end for changing the relative angular throw of said arm and lever, substantially as described.

16. In a carbureter, the combination of a valve-casing; a mixing-chamber in said casing, having a fuel-inlet communicating there-

with; a needle-valve controlling said fuel-inlet; a member supporting the needle-valve and having threaded connection with the casing and being adapted when rotated to move said needle-valve for varying the discharge of fuel through said inlet, said needle-valve being adjustable relatively of said member; an arm on the member for rotating the same; an operating-lever, and a link connecting said arm and lever, said link being adjustable at one end for changing the relative angular throw of said arm and lever, and said arm and lever being suitably arranged to permit of said adjustment of throw without disturbing the relative position of said arm for a certain position of the lever, substantially as described.

Signed at Chicago this 7th day of July, 1904.
